UNITED STATES PATENT OFFICE.

ANDREW R. RIDDERSTROM, OF NAHANT, MASSACHUSETTS, ASSIGNOR TO BEACON FOLDING MACHINE COMPANY, OF LYNN, MASSACHUSETTS, A CORPORATION OF MASSACHUSETTS.

FOLDING MACHINE AND METHOD.

Application filed February 11, 1924. Serial No. 692,168.

The present invention relates to methods of and machines for operating upon flexible material, and more particularly to methods of and machines for folding the margins of 5 shoe uppers, such as vamps, quarters, tips, tongues and the like.

Folding machines of the above-described character, of the step-by-step-feed type, are provided with a plow that initiates a fold 10 in the margin of the material, and with a fold presser that presses down the fold initiated by the plow. When folding shoe uppers provided with sharply convex curves, it is necessary to turn the stock very abruptly, 15 which often results in moving the stock out of range of the fold presser. If the pressing face of the fold presser be increased, so as to enable it to operate upon stock having sharply convex curves, the increased area of the 20 fold presser will engage the free edge of straight portions of the folded margin prematurely. An object of the present invention is to adapt the fold presser for operation upon stock having both convex and straight 25 margins, and with this end in view, a feature of the invention resides in increasing the pressing face of the fold presser to enable it to operate upon sharply convex margins, but providing it with a recess which the free 30 edge of a straight folded margin may enter to prevent its becoming pressed prematurely.

The product of present-day folding machines has a tendency to twist. This tendency becomes very noticeable when the stock 35 is very narrow. The twisting effect is believed to be due to the fact that the folded portions of the margin are pressed against the stock at points a little to one side of the normal to the margin. By lifting the stock 40 towards the folded margin at the moment of pressing, this twisting tendency is reduced; and a further object of the invention is to provide a method and machine for effecting this result.

45 Other and further objects will appear hereinafter. With these objects in view, the invention consists of the improved method and machine a preferred embodiment of which is illustrated and described herein. It 50 is intended to express in the appended claims all the novelty that the invention may possess.

In the accompanying drawings, Fig. 1 is an elevation, with parts broken away and

other parts omitted, for clearness, of the 55 forward portion of a machine constructed according to a preferred embodiment of the present invention; Fig. 2 is a section taken upon the line 2—2 of Fig. 1, looking in the direction of the arrows; Fig. 3 is a 60 section taken upon the line 3—3 of Fig. 4, looking in the direction of the arrows, upon a larger scale; Fig. 4 is a section taken upon the line 4—4 of Fig. 3, looking in the direction of the arrows; Fig. 5 is a view corresponding to Fig. 4, showing the operation upon a convex curve; Fig. 6 is a section taken upon the line 6—6 of Fig. 3, looking in the direction of the arrows; and Fig. 7 65 is a side elevation showing the mounting of 70 the knives.

The invention is illustrated in its preferred form as applied to a folding machine for folding the margins of shoe uppers, such as tongues, but is applicable also to the 75 folding of binding strips around shoe uppers to which they are sewed and to other uses. The machine is provided with a lower feed block 41 and an upper feed point 30, between which a shoe upper, like a tongue 80 2, is adapted to be intermittently gripped, and by which it is adapted to be fed or advanced, step by step, over a platform or support 24. During this feed movement, the edge of the shoe upper first engages a gage 85 436, that is secured at 438 to the upper end of a bracket 61, after which it is advanced to and past two cooperating knives 352 and 353. The knife 353 is stationary, but the knife 352 may be thrown into operation, at 90 the will of the operator, so as to snip or slit the margin of the upper, at will, and to this end, it is pivoted at 356 on the upper end of the same bracket 61, and is connected by a link 354 to mechanism (not shown) under the control of the operator, as is more fully explained in a copending application, Serial No. 652,169, filed July 17, 1923. Whether the margin is snipped or not, as 95 may be desired, it is then advanced beyond a retainer 153 that acts to hold the stock against the support during pauses in the feed, but that is raised during the feeding movement. The other functions performed by the retainer and the retainer-operating mechanism will not be described herein, because fully described in Patents Nos. 1,527, 895 and 1,527,396, granted February 24, 1925, 100 105

because other retainers and other retainer-operating mechanisms may be employed without departing from the present invention. A plow 32 then acts to initiate a fold 5 in the margin of the material, and a fold presser 42 subsequently presses the fold flat against the body of the material. The feed mechanism remains idle while the fold presser is pressing the fold, and the fold presser 10 is ineffective during the feeding of the work.

The fold presser 42 is floatingly pivoted at 146, Fig. 1, to a link 148 the other end of which is operated from a driving shaft 66, as is more fully described in the above- 15 mentioned patents. The exterior surface of the fold presser is cylindrical, as shown at 156, Figs. 1 and 3, so as to rock within a cylindrical bearing 158 provided at the free end of an arm 160 the other end of which 20 is pivoted at 162, Fig. 2. The fold presser is spring-pressed towards the support 24 by a compression spring 166, Fig. 2, mounted upon a rod 168 extending through an opening (not shown) in the arm 160 and screw- 25 threaded into the frame. By means of this construction, the fold presser is pivotally actuated in a plane at right angles to the plane of feed, with a yielding action of the fold presser upon the fold, relieving the 30 strain thereon, while permitting a positive separation of the fold presser from the upper by the link 148.

The feeding mechanism, comprising the feed block 41 and the feed point 30, is also 35 driven from the driving shaft 66 by mechanism more fully described in the above-named patents. The feed block 41 is shown more particularly in Fig. 1 as rigidly secured to, or integral with, a holder 93 that is 40 secured, as by a set screw (not shown), to a rocking or oscillating support 94. The rocking support is pivotally mounted about a rod 96 that is secured to the frame of the machine by a screw (not shown). The feed 45 point 30 is pivotally mounted at 110 upon the rocking support 94, so as to be rocked therewith and with the lower feed block 41.

An arm member 36 is also pivotally mounted to rock or oscillate about the rod 50 96. The member 36 is provided with a diagonally disposed cylindrical opening 100 within which is slidingly mounted a diagonally cylindrical block 102 the upper flat face of which is substantially horizontal, 55 as shown at 104. The angle of inclination of the opening 100 is preferably in the neighborhood of thirty degrees. The cylindrical block 102 is adapted to be actuated by an eccentric or crank pin 106 of the driving 60 shaft 66. The eccentric or crank pin is rotatably mounted in the block 102 and extends through an opening 108 of the rocking member 36. Rotative movement of the shaft 66 will be converted by the eccentric into 65 combined sliding and oscillating or rotative

movement of the block 102 and this, in turn, will effect a rocking movement of the rocking member 36 about the rod 96. A compression coiled spring 38, interposed between the rocking support 94 and the rocking member 70 75 36, yieldingly connects the rocking support 94 to the rocking member 36 to cause them to rock or oscillate together, as a unit, as is described more fully in the said copending application, Serial No. 652,169 and in another copending application, Serial No. 668,345, filed October 13, 1923. The coiled spring 38 yieldingly maintains an arm 39 of the rocking support 94 in engagement with an adjustable portion 40 of the rocking member 36. The adjustable portion 40 of the rocking member 36 is shown as a set screw.

The feed point 30 is normally yieldingly maintained in contact with the feed block 41 by a compression coil spring 112 coiled about a threaded rod 114 extending through an opening 116 in the feed-point arm 118 and secured at 43 to the rocking support 94. By means of the threads upon the rod 114, the pressure of the spring 112 upon the feed point may be adjusted, the ends of the spring being confined between the feed-point arm 118 and a knurled nut 124 that is 80 threaded upon the rod 114. The feed-point arm 118 is provided with an adjustable screw 120. The upper face 104 of the block 102 is adapted to engage the screw 120, thereby to raise the feed point in opposition to the pressure of the spring 112. An additional adjustable member 123 is provided to prevent the feed point becoming lowered into contact with the feed block when the machine is running idly, thereby preventing the feed point pounding uselessly against the feed block when no stock is interposed. 100

As the driving shaft 66 is rotated, the rocking support 94 is rocked up and down, as viewed in Fig. 2, imparting an oscillating movement to the lower feed block 41 and the upper feed point 30 which are carried thereby. During the down movement, the feed point 30 will be separated from the feed block 41 by the action of the cylindrical block 102, which then occupies its upper positions. During the up movement, the block 102 will lie in the lower portions of the cylindrical opening 100, and the feed point will be spring-pressed into engagement with the feed block, which will 110 thus advance to the fold presser the upper clamped therebetween. 115

The plow 32 is intermediately carried upon a lever 34 one end of which is pivoted at 130 to the frame of the machine in such fashion as to permit the lever to pivot in a horizontal plane. The plow therefore moves in substantially the plane of the upper, but at an angle to the direction of feed. The other end of the lever 34 is yieldingly 125 130

5 maintained in engagement with a projection 37 of the arm 36 by a leaf spring 132 that is fixed to the arm 36 in any desired manner, as illustrated at 140. When the arm 36 is 10 rocked downward, as viewed in Fig. 2, the projection 37 will engage the lever 34 and cause the plow 32 to swing open about its pivotal point 130, in the direction of the curved arrow, Fig. 4. When the arm 36 is 15 rocked in the opposite direction, the spring 132 will cause the plow to pivot in the opposite direction. The plow is thus oscillated once corresponding to each rocking movement of the rocking arm 36.

15 Summarizing the operation of the preferred machine, as thus far described, the shoe upper is advanced over the support 24, step by step, by the feed point 30 and the feed block 41; the plow 32 is actuated 20 during pauses in the feed to initiate a fold in successive portions of the margin, step by step; and the fold presser 42, is actuated step by step, during pauses in the feed, to press flat the folds successively initiated by 25 the fold presser during immediately prior pauses in the feed. Each folded portion is pressed while the next succeeding portion is being folded. The feed elements may feed by shorter or longer feed steps, as desired, 30 and to this end, in the specific embodiment of the invention herein illustrated, the rocking member 36 and the rocking support 94 may be rocked or oscillated as a unit, provision being made, however, for adjustably limit- 35 ing the degree of oscillation of the rocking support 94, and, therefore, adjustably limiting the lengths of the feed steps of the feed block 41 and the feed point 30 that are carried by the rocking support 94, all as is more 40 fully described in the above-named applications, Serial Nos. 652,169 and 668,345.

The fold pressers heretofore employed in commercial folding machines have possessed a fold-pressing area corresponding some- 45 what to the area indicated at 5. So long as straight margins only are operated on, a fold presser of this character is fully satisfactory, as will be understood from an inspection of Fig. 4. When convex margins 50 are encountered, the stock is liable to be turned out of the range of action of the fold presser, as will be clear from Fig. 5. The fold presser is therefore provided with an extension 7 that extends forward of the portion 5, at right angles to the direction of feed in a position beyond the folded portion of the margin where the folded portion is 55 straight, as illustrated in Fig. 4, so as to engage convex margins of the stock, as illustrated in Fig. 5. Such an extension would be liable to engage the free edge of the folded margin, at 9, Fig. 4, before the fold had yet been pressed down, which would exert tension upon the portion 11 of the margin in 60 rear of the portion 9. The fold presser is

therefore provided with a recess 13 between the portions 5 and 7, into which the free edge 9 of the margin may enter without imposing any strain upon the stock.

60 The fold presser presses the stock against an anvil 15 that is raised above the plane of the support 24, thereby reducing the above-described twist. The anvil 15 is substantially parallel to the support 24, so as to raise parallel to itself the whole portion 65 of the stock adjacent to the folded margin against which the folded margin is to be pressed.

Many details of the illustrative machine have not been illustrated herein, and many 70 illustrated parts have not been described, because unnecessary to an understanding of the present invention, and because the invention may equally well be embodied in other machines. Full particulars of the illustrative machine may be obtained in the aforesaid patents and applications. The elements of novelty, furthermore, though fully explained, are by no means restricted to the exact embodiments thereof that are illustrated and described herein. Modifications and changes will readily occur to persons skilled in the art, and all such are considered to fall within the scope of the invention, 75 as defined in the appended claims.

80 What is claimed is:

1. A folding machine having, in combination, means for feeding sheet material, 100 means for folding a portion of the material across the plane of the sheet, and a fold presser for pressing the folded material, the fold presser having a fold-pressing face and an extension of the fold-pressing face disposed substantially at right angles to the line of feed in a position a substantial distance beyond the folded portion of the material when the folded portion of the material is straight.

2. A folding machine having, in combination, means for feeding sheet material, 110 means for folding a portion of the material across the plane of the sheet, and a fold presser for pressing the folded material, the fold presser having a fold-pressing face and an extension of the fold-pressing face disposed substantially at right angles to the line of feed in a position beyond the folded portion of the material when the folded portion of the material is straight, and being provided with a recess between the fold- 115 pressing face and the extension, the recess being disposed on the side of the fold presser adjacent to the folding means.

3. A method of folding the margin of a sheet of flexible material that comprises 120 folding the margin, raising the portion of the sheet adjacent to the folding margin parallel to itself, and pressing the folded margin against the raised portion of the sheet.

4. A method of folding the margin of a 125

sheet of flexible material that comprises feeding the material step by step, folding successive portions of the margin, successively raising the portions of the sheet adjacent to the successively folded portions of the margin parallel to themselves, and pressing the folded portions of the margin against the successively raised portions of the sheet.

5. A folding machine having, in combination, a support, means for feeding material over the support, means for folding the material, a fold presser for pressing the folded material, and an anvil raised above and parallel to the support against which the fold presser is adapted to press the folded portions of the material.

10. A folding machine having, in combination, a support, means for feeding material

over the support, a plow for folding the margin of the material, and a fold presser 20 and an anvil for pressing the folded margin, the fold presser having a fold-pressing face and an extension of the fold-pressing face disposed substantially at right angles to the line of feed in a position beyond the folded 25 portion of the margin when the folded portion of the margin is straight and being provided with a recess between the fold-pressing face and the extension, and the anvil being raised above and parallel to the support. 30

In testimony whereof, I have hereunto subscribed my name this 9th day of February, 1924.

ANDREW R. RIDDERSTROM.
